UNITED STATES PATENT OFFICE.

RALPH FODERARO, OF ARCHBALD, AND GEORGE W. WILMOT, OF HAZLETON, PENNSYLVANIA.

DISCHARGE-CONTROLLING MEANS FOR JIGS.

1,324,588.

Specification of Letters Patent.

Patented Dec. 9, 1919.

Application filed March 18, 1916, Serial No. 84,999. Renewed October 17, 1919. Serial No. 331,492.

To all whom it may concern:

Be it known that we, RALPH FODERARO, a citizen of the United States, and a resident of Archbald, county of Lackawanna, State 5 of Pennsylvania, and GEORGE W. WILMOT, a citizen of the United States, and a resident of Hazleton, county of Luzerne, State of Pennsylvania, have invented certain new and useful Improvements in Discharge-Controlling Means for Jigs, of which the following is a specification.

While our invention may be used to advantage for washing and separating ores in general from stone and other matter which 15 it is desired to eliminate, it is particularly efficient when used for washing coal and separating the slate and stony particles therefrom.

One object of our invention is to provide 20 means whereby a layer of slate is maintained at all times upon the controlling discharge gate to thereby prevent the slate from passing out too freely and also to prevent wastage by reason of the passage of particles of 25 coal through the opening intended for the discharge only of slate and other material, such as stone, which it is desired to eliminate and remove.

A further object of our invention is to 30 provide an improved construction of means for controlling the position of the discharge gate with respect to the lower edge of the upright plate over the upper edge of which the coal or corresponding lighter particles of 35 ore or other material is discharged.

Other objects and advantages of our invention will be referred to and pointed out in the detailed description of our invention which follows or will be apparent from such 40 description.

In order that our invention may be clearly understood and its advantages more fully appreciated reference should be had to the accompanying drawings in which we have 45 illustrated one form of construction embodying our invention. It will be understood, however, that changes in the details of construction may be made within the scope of the claims without departing from the principle of our invention.

In the drawings:—

Figure 1 is a vertical sectional view of a portion of a jig embodying our invention, said view being taken on the line 2—2 of 55 Fig. 2;

Fig. 2 is a top plan view of a portion of a jig embodying our invention; and

Fig. 3 is an end view of the same.

Referring to the drawings:—1 designates a jig screen having sides 2. We have not 60 shown means for supporting and operating the jig screen because such means constitutes no part of our invention. For ascertaining the construction of a jig of the character of that to which our invention is applied reference may be had to Letters Patent of the United States No. 1,055,730, issued 65 March 11, 1913 to Henry W. Falker.

Extending forwardly from the forward end of the jig screen is a gate 3 which controls the discharge of the slate, stone and like material, which it is desired to eliminate, underneath the lower edge of the upright breast plate 4. The gate 3 is provided with upturned side flanges 5 which are situated upon the outer sides of the opposite sides 2 of the jig screen. The rear ends of these side flanges are extended and are bent or looped around a shaft 8 which is supported in bearings 9 secured upon the sides 2 of 70 the jig screen. It is apparent that the controlling gate 3 is pivotally supported at what may be termed its rear edge. The side flanges 5 of the gate 3 are provided at their forward ends with projections 10 to which 75 are secured the lower ends of a yoke-shaped member 11. 12 designates a rod having adjustable connection with the upper portion of the yoke-shaped member 11. The upper end of the said rod is connected with the 80 forward end of a lever 15 pivoted at 16 between the upper ends of the angular bars 17 which are supported at their lower ends upon the opposite sides 2 of the jig screen. To the opposite end of the said lever 15 a 85 weight 18 is secured, said weight being adjustable to different positions upon the said lever, toward and away from the pivot 16. It may be secured in any position to which it may be adjusted by means of a binding 90 screw 19.

20 designates an arm secured to or connected with the lever 15 at a distance from the pivot 16 on the opposite side of the latter from the point of connection of the rod 12 105 to such lever. The said arm is extended forwardly and in the construction as illustrated is concentric with the pivot 16.

21 designates a weight which is supported upon the said arm 20 and is adjustable there-

on. It is apparent that as the weight 21 is adjusted toward the lower outer end of the said arm it approaches a vertical line extending through the pivot 16 thereby decreasing the leverage of the force of gravity 5 of the said weight 21 upon the lever 15. It is also apparent that as the lever 15 moves upon its pivot as indicated by the dotted lines 22 the horizontal distance between the weight 18 and the pivot 16 decreases while 10 the horizontal distance between the weight 21 and the said pivot increases. By this means a more nearly constant force is exerted at all times through the yoke-shaped member 11 and rod 12 upon the forward edge of the controlling gate 3 tending to hold the same upwardly against the lower edge of the upright plate 4. Preferably the weight 18 normally should be situated approximately in a horizontal plane through 15 the axis of the pivot of the lever 15, while the weight 21 normally should be situated at a point below such plane. This is desirable in order that when the outer swinging 20 end portion of the lever 15 is lifted or elevated, the horizontal distance between the pivot 16 and a vertical line through the weight 18 will decrease, while the horizontal distance between the said pivot and a vertical line through the weight 21 will be increased. It will, of course, be understood 25 that in actual practice the weight 18 may occupy a position a short distance below the horizontal plane through the pivotal axis 30 of the lever 15.

The forward end of the gate 3 (which is of sheet metal) is provided with a depending flange 25 the lower edge of which is also flanged as shown at 26. Secured to and 35 supported upon the flanges 25 and 26 is a transversely extending plate 30, the upper edge of which extends above the plane of the upper surface of the gate 3. The plate 30 is provided with slots 31 through which 40 binding and holding bolts 32 extend. The plate 30 may be adjusted to different positions and secured and held in such positions by tightening the bolts 32 as is obvious.

For the purpose of adjusting the said 45 plate 30 and also for the purpose of supporting the lower edge thereof we have provided the adjustable bolts 33 which are engaged with and extend through the forwardly extending flange 26 at the lower edge 50 of the flange 25. The presence of the upper edge portion of the plate 30 projecting beyond or above the upper surface of the plate 3 causes the slate to pile up to a greater or less extent upon the said plate so that it 55 forms a layer thereupon and thereby prevents the slate and other particles which it is desired to eliminate from passing too freely along the bottom of the said gate. Without the presence of the plate 30, which 60 may be described as a retarding plate, it is

found that it frequently happens that a somewhat larger piece of slate, or possibly even a piece of coal, will lodge between the said controlling gate 3 and the lower edge of the upright plate 4 and hold the gate 70 open and thus prevent the weights 18 and 21 from closing the said gate and thereby permitting the slate to flow out altogether too freely and in many instances permitting the escape or discharge of coal underneath the 75 lower edge of the said upright plate 4.

Coal as it is discharged over the upper edge of the plate 4 passes through a chute 35 and is discharged on to the endless conveyer 36 and is removed thereby. The slate 80 and other material discharged beneath the lower edge of the upright plate 4 is removed or carried away by the endless conveyer 37.

We claim:

1. The combination of a controlling discharge gate for a jig, said gate being pivotally supported at its rear edge, a lever pivotally supported intermediate its ends a distance above said gate, a connection between one end of said lever and the forward swinging edge of said gate, and a plurality of weights supported by the portion of said lever upon the opposite side of its pivotal support, one of the said weights normally being situated at a point in or near a horizontal plane through the pivotal axis of said lever, and the other one of said weights normally being situated at a point below said plane, whereby when the outer swinging end of said lever is elevated, the leverage of the first of said weights decreases and that of the other of said weights increases. 100

2. The combination of a controlling discharge gate for a jig, said gate being pivotally supported at its rear edge, a lever pivotally supported intermediate its ends, said lever being situated a distance above said gate, an adjustable connection between one end of said lever and the forward swinging edge of said gate, a plurality of weights 105 supported upon the opposite end portion of said lever, one of the said weights normally being situated at a point in or near a horizontal plane extending through the pivot of said lever, and the other one of said weights 110 being situated at a point below said plane, whereby the leverage of the first of said weights decreases as the portion of said lever by which it is carried is elevated and the leverage of the other of said weights 115 simultaneously increases, so that the force due to gravity exerted by said weights remains practically constant.

3. The combination of a controlling discharge gate for a jig, said gate being pivotally supported at its rear end, a lever spaced above said gate and being pivotally supported intermediate its ends, a connection between one end of said lever and the forward swinging end of said gate, the opposite end 120

- portion of said lever being provided with a downwardly and forwardly extending arm, and weights, one of which is supported upon the opposite end portion of said lever and 5 the other one of which is supported upon the said arm.
4. The combination of a controlling discharge gate for a jig, said gate being pivotally supported at its rear edge, a lever 10 spaced above said gate and being pivotally supported intermediate its ends, a connection between one end of said lever and the forward swinging end of said gate, the opposite end portion of said lever being provided with a forwardly curved arm, said arm being concentric with the pivot of said lever, a weight adjustably supported upon the said opposite end portion of the lever, and a weight supported upon the said arm.
- 20 5. The combination of a controlling discharge gate for a jig, said gate being pivotally supported at its rear edge, a lever pivotally supported intermediate its ends a distance from said gate, means for connecting 25 one end of said lever with the forward swinging edge of said gate, a weight supported upon the outer swinging end portion of the said lever, an arm connected with the outer swinging portion of said lever, said
- arm extending downwardly and being concentric with the pivotal axis of said lever and a weight secured upon said arm.
6. The combination of a controlling discharge gate for a jig, said gate being pivotally supported at one edge, a lever pivotally supported intermediate its ends a distance from said gate, a connection between one end of said lever and the swinging edge of said gate and a plurality of means associated with the opposite end portion of said lever and exerting force thereon in opposition to the force exerted upon the said lever by the said gate, one of the said means being situated normally in or near a horizontal plane through the pivotal axis of said lever, and the other of said means normally being situated below the said plane, whereby the force exerted by the first of said means decreases and that exerted by the other of said means increases as the portion 50 of the said lever with which the said means are associated is raised.

In testimony that we claim the foregoing as our invention we have hereunto signed our names this 16 day of March, A. D. 1916. 55

RALPH FODERARO.
GEORGE W. WILMOT.
